UNITED STATES PATENT OFFICE.

JAMES CUNNING, OF INDIANAPOLIS, INDIANA.

REFRIGERATOR-CAR.

Patented Feb. 24, 1914.

1,088,130.

Specification of Letters Patent.

Application filed January 22, 1912. Serial No. 672,665.

To all whom it may concern:

Be it known that I, JAMES CUNNING, a citizen of the United States, residing at Indianapolis, in the county of Marion and State of Indiana, have invented a new and useful Refrigerator-Car, of which the following is a specification.

It is the object of my invention to increase the efficiency of refrigerator cars, to utilize more of the heat-absorbing capacity of the ice or other cooling material used, and to diminish the required number of rechargings with ice or other cooling material. To accomplish this, the brine from the melting of the salted ice used is sprayed through tubes or pipes in the car and preferably near the top thereof, these pipes being open at both ends so that the air in the car will be circulated through them by the action of the spray. The brine may be used a number of times, if desired, means being provided for preventing it from escaping into the car. The spraying is accomplished by means of a suitable pump, preferably driven 25 from the car axle.

The various novel features of my invention will appear from the description and drawings, and will be particularly pointed out in the claims.

30 Figure 1 is a section, on the line 1-1 of Fig. 2, through a refrigerator car embodying my invention; Fig. 2 is a section on the line 2-2 of Fig. 1; Fig. 3 is an enlarged section on line 3-3 of Fig. 2; Fig. 4 is a 35 fragmentary sectional view on a larger scale through the ice tank and brine tank, being taken on the line 4-4 of Fig. 3; and Fig. 5 is a fragmentary view showing the brine nozzles in the circulation tubes.

40 Located in each end of the car body 10 is an ice receptacle 11, preferably built up of slats and lined with wire netting to allow the easy circulation of air while retaining the ice. In some cases there may be but one ice receptacle. Extending completely under one ice receptacle 11 is a brine tank 12, while extending part way under the other is another brine tank 13, these two tanks being connected by an equalizing pipe 45 14 to equalize the brine level therein. The remainder of the space under said second ice receptacle is housed in to form a chamber 15, in which is a pump 16. Below each ice receptacle, and over the chamber 15, and tank 13 in one case and the tank 12 in the other, is a sloping cover or roof 17 which

extends nearly across the car, leaving a narrow slot between its lower end and a wall of the corresponding brine tank to allow the brine which drops through from the superposed ice receptacle 11 to trickle into a filter 18, whence it passes to the brine tank. The roofs 17 effectually prevent the brine in the tanks from splashing out upon sudden changes in the speed of the car.

45 The pump 16 is preferably driven in any suitable manner, as by a belt 20, from one of the axles 21 of the car, so that whenever the car is in motion it pumps brine from the tank 13 through a pipe 16' into a pipe 22, which preferably leads to the middle of the car near the top and there extends crosswise of the car. The crosswise section of the pipe 22 is supplied with one or more spraying nozzles 23 projecting lengthwise of the car in both directions, into the ends of air circulation tubes 24. The tubes 24, which are preferably rectangular in cross section, slant slightly downward toward the ends of the car to points 25, and are then bent upward at 26; the slant is preferably slightly greater than the maximum grade on railroads. Pipes 27 lead from the bottoms of the tubes 24 at the points 25, and carry off the brine therefrom to the brine tanks 12 85 and 13, the pipes 27 preferably projecting nearly to the inlet openings of the overflow pipes 28 so that in case the brine in the tanks reaches the maximum level the overflow will be mainly the brine which has been heated 90 in the tubes 24.

50 The tubes 24 are open at both ends, the openings at the middle of the car preferably being at the top of the tubes at 30 and the openings at the ends of the car preferably 95 being at the bottom of the tubes at 31. The brine sprays in the tubes 24 cause the air from the car to enter the openings 30, to pass lengthwise along the tubes 24 and be cooled and dried by the sprays in such passage, and to leave the tubes 24 through the openings 31, thus producing an effective air circulation in the car. The drying is due to the condensation of water vapor as the air is cooled. The brine sprayed through the tubes 24 absorbs both the heat and the odors from the air in the car, its heat-absorbing power thus being put to better and more effective use than in the refrigerator cars where the brine is allowed to run out without being sprayed. By thus using brine sprays to cool the air in the car, the melting

of the ice in the receptacles 11 is retarded, while at the same time the air in the car is maintained even cooler than that in refrigerator cars in which the brine from the melting ice is not thus sprayed. Thus the cars need fewer icings. Moreover the car is maintained both sweeter and drier. Furthermore, the cars may be used, as in cold weather, for keeping goods warm, or above freezing temperature. In such cases no ice is used, but the tanks 12 and 13 are filled with comparatively warm water or other liquid, and this water is sprayed through the tubes to give off heat to the air in the car. Often ordinary hydrant water, with occasional drainings and refillings, is sufficient for this purpose.

The term "brine" is used here to denote any cooling liquid medium, salt water formed by the melting of salted ice being the one generally used. Satisfactory results are attained in some cases by the use of drippings from unsalted ice.

My invention is capable of considerable modification and I aim to cover all modifications which do not involve a departure from the spirit and scope of my invention as set forth in the following claims.

What I claim as new is:

- 80 1. A refrigerator car having one or more receptacles for ice, said receptacles being formed of slats to allow a circulation of air therethrough, one or more tanks for receiving the liquid from said receptacle or receptacles, said tank or tanks being arranged below the ice receptacle or receptacles and provided with inclined roofs which at their lower ends open into such tanks, a pump driven from the car axle and operating to
- 35 pump the liquid from such tank or tanks and discharge it into the air within the car, one or more tubes inclosing the water as it is thus discharged and open at their opposite ends to allow ingress and egress of air, and
- 40 a return pipe or pipes for carrying off the liquid from said tube or tubes to the tank or tanks, said tank or tanks being provided with one or more overflow outlets the entrances to which are in proximity to the discharge ends of the return pipes so that in case of overflow it is mainly the liquid returned through said return pipes which overflows.
- 45 2. A refrigerator car having one or more receptacles for ice, one or more tanks for receiving the liquid from said receptacle or receptacles, a pump driven from the car axle and operating to pump the liquid from such tank or tanks and discharge it into the air within the car, one or more tubes inclosing the water as it is thus discharged and open at their opposite ends to allow ingress and egress of air, and a return pipe or pipes for carrying off the liquid from said tube or

being provided with one or more overflow outlets the entrances to which are in proximity to the discharge ends of the return pipes so that in case of overflow it is mainly the liquid returned through said return pipes which overflows.

3. A refrigerator car having one or more receptacles for ice, one or more tanks for receiving the liquid from said receptacle or receptacles, a pump operating to pump the liquid from such tank or tanks and discharge it into the air within the car, one or more tubes inclosing the water as it is thus discharged and open at their opposite ends to allow ingress and egress of air, and a return pipe or pipes for carrying off the liquid from said tube or tubes to the tank or tanks, said tank or tanks being provided with one or more overflow outlets the entrances to which are in proximity to the discharge ends of the return pipes so that in case of overflow it is mainly the liquid returned through said return pipes which overflows.

4. A refrigerator car having one or more receptacles for ice, one or more tanks for receiving the liquid from said receptacle or receptacles, a pump driven from the car axle and operating to pump the liquid from such tank or tanks and discharge it into the air within the car near the top thereof, and means for collecting the liquid thus discharged and returning it to said tank or tanks, said tank or tanks being provided with one or more overflow outlets the entrances to which are in proximity to the discharge of said returning means so that in case of overflow it is mainly the liquid so returned which overflows.

5. A refrigerator car having one or more receptacles for ice, sides of said receptacles being formed of slats to allow a circulation of air therethrough from and to the body of the car, one or more tanks for receiving the liquid from said receptacle or receptacles, said tank or tanks being arranged below the ice receptacle or receptacles and provided with inclined roofs which at their lower ends open into such tanks, a pump driven from the car axle and operating to pump the liquid from such tank or tanks and discharge it into the air within the car and means for collecting the liquid thus discharged and returning it to said tank or tanks.

6. A refrigerator car having one or more receptacles for ice, sides of said receptacles being formed of slats to allow a circulation of air therethrough from and to the body of the car, one or more tanks for receiving the liquid from said receptacle or receptacles, said tank or tanks being arranged below the ice receptacle or receptacles and provided with inclined roofs which at their lower ends open into such tanks, a pump operating to pump the liquid from such tank or tanks

and discharge it into the air within the car, and means for collecting the liquid thus discharged and returning it to said tank or tanks.

5 7. A refrigerator car having one or more receptacles for ice, one or more tanks for receiving the liquid from said receptacle or receptacles, said tank or tanks being arranged below the ice receptacle or receptacles and provided with inclined roofs which at their lower ends open into such tanks, a pump operating to pump the liquid from such tank or tanks and discharge it into the air within the car, and means for collecting the liquid thus discharged and returning it to said tank or tanks, said tank or tanks being provided with one or more overflow outlets the entrances to which are in proximity to the discharge of said returning means so that in case of overflow it is mainly the liquid so returned which overflows.

10 8. A refrigerator car having one or more receptacles for ice, sides of said receptacles being formed of slats to allow a circulation of air therethrough from and to the body of the car, one or more tanks for receiving the liquid from said receptacle or receptacles, a pump operating to pump the liquid from such tank or tanks and discharge it into the air within the car, and means for collecting the liquid thus discharged and returning it to said tank or tanks.

15 9. A refrigerator car having one or more receptacles for ice, one or more tanks for receiving the liquid from said receptacle or receptacles, a pump operating to pump the liquid from such tank or tanks and discharge it into the air within the car near the top thereof, and means for collecting the liquid thus discharged and returning it to said tank or tanks, said tank or tanks being provided with one or more overflow outlets the entrances to which are in proximity to the discharge of said returning means so that in case of overflow it is mainly the liquid so returned which overflows.

20 10. A refrigerator car having one or more receptacles for ice, one or more tanks for receiving the liquid from said receptacle or receptacles, a pump driven from the car axle and operating to pump the liquid from such tank or tanks and discharge it substantially horizontally into the air within the car, and one or more nearly horizontal tubes inclosing the liquid thus discharged and open at

their opposite ends to allow ingress and egress of air.

25 11. A refrigerator car having one or more receptacles for ice, one or more tanks for receiving the liquid from said receptacle or receptacles, a pump operating to pump the liquid from such tank or tanks and discharge it substantially horizontally into the air within the car, and one or more nearly horizontal tubes inclosing the liquid thus discharged and open at their opposite ends to allow ingress and egress of air.

30 12. A refrigerator car having one or more liquid containing tanks, in combination with a pump driven from the car axle for discharging the liquid from said tank or tanks substantially horizontally into the air in the car, nearly horizontal tubes surrounding the liquid thus discharged and open at the ends to allow ingress and egress of air, and pipes for carrying the liquid from said tubes back to the tank or tanks.

35 13. A refrigerator car having one or more liquid containing tanks, in combination with a pump for discharging the liquid from said tank or tanks substantially horizontally into the air in the car, nearly horizontal tubes surrounding the liquid thus discharged and open at the ends to allow ingress and egress of air, and pipes for carrying the liquid from said tubes back to the tank or tanks.

40 14. A refrigerator car having one or more liquid containing tanks, in combination with a pump for discharging the liquid from said tank or tanks substantially horizontally into the air in the car, and nearly horizontal tubes surrounding the liquid thus discharged and open at the ends to allow ingress and egress of air.

45 15. A refrigerator car having one or more liquid containing tanks, in combination with a pump driven from the car axle for discharging the liquid from said tank or tanks substantially horizontally into the air in the car, and nearly horizontal tubes surrounding the liquid thus discharged and open at the ends to allow ingress and egress of air.

50 In witness whereof, I have hereunto set my hand and seal at Indianapolis, Indiana, this thirteenth day of January, A. D. one thousand nine hundred and twelve.

JAMES CUNNING. [L. S.]
